RESILIENT VISE-JAW FACEPLATE HAVING
MAGNETIC INSERT OF LESSER THICK-
NESS

Richard T. Philips, Seattle, Wash.

Application March 26, 1951, Serial No. 217,588

4 Claims. (Cl. 81—38)

1

This invention relates to improvements in a resilient vise-jaw face-plate having magnetic insert of lesser thickness and, more particularly, to an elastic or resilient vise jaw facing element or the like.

It is among the more important objects of this invention to provide a resilient or elastic vise jaw pad, which is easily constructed at low cost, and which is extremely simple to attach to a vise jaw or remove therefrom, without the use of tools, or any particular skill on the part of the user; which will preclude the marring of work being gripped therebetween when used in pairs and which is not easily displaced from the point of use under the normal conditions attendant upon the vise's use; which will accommodate irregularities in both the vise jaw faces and the work to be gripped; and which even through embodying substantial attaching means will not mar a workpiece applied therebetween.

These and other objects of this invention will be apparent during the course of the following specification of the invention when taken in view of the disclosure made in the attached drawing in which:

Figure 1 is a perspective view of resilient vise jaw pad according to my invention;

Figure 2 illustrates the application of a pair of jaw pads to the jaws of a vise;

Figure 3 is an enlarged fragmentary detailed sectional view through a portion of a pair of vise jaws equipped with my pads and showing the action during gripping of workpiece;

Figure 4 illustrates in perspective a magnet employed in my vise jaw pad;

Figure 5 is a rear view of modified form of elastic pad; and

Figure 6 is a vertical sectional view of a pad as shown in Figure 5.

Referring to Figure 2, I have there shown a vise of conventional structure having the usual stationary jaw 10 and movable jaw 12 that moves toward and away from the other jaw by means of the screw bar 14 when manually manipulated by the cross rod 16. The gripping face of each of the jaws 10 and 12 is provided with a rubber or resilient pad 18 of the type more clearly seen in Figure 1.

Each pad 18 comprises a gripping face 20 that may be geometrically grooved as shown, or otherwise roughened, to provide a degree of frictional contact thereon when brought against a workpiece. Preferably one edge 22 is designated the upper edge and the edges at right angles thereto are the ends 24, 24.

2

Intermediate the ends and sides of the pad 18 is provided a pair of magnets 26, 26 spaced apart from each other in a symmetrical manner and so arranged in the pad that they lie with their gripping faces in the same plane as the rear face 28 of the pad. These magnets are more fully shown in the enlarged perspective view of Figure 4 to comprise a cylindrical body 30 that is laterally grooved at 32 to provide pole pieces 34, 34 the faces of which are preferably co-planar with the rear face of the pad 18.

Such magnets as are most useful for my purposes are the aluminum-nickel-cobalt type sometimes more concisely described as "permanent" magnets.

In using the cylindrical form, for attachment of the magnets within the pads, I form passages 27, 27 through the pad into which the magnets are pressed. By arranging that the thickness of the pad is greater than the thickness of the magnet body and its pole pieces, it will be seen that the gripping faces of the magnet 26 can be flush with the rear face 28 of the pad while the other magnet face underlies the gripping or work-contacting face of the pad. That condition is shown in Figures 1, 3 and 6, and the reason for it lies in the fact that when the vise jaws are closed upon a workpiece, as W in Figure 3, the latter will be gripped by the pad material but not between opposed magnets under ordinary conditions and thereby marring of the workpiece is avoided.

The jaw pad 18' of Figures 5 and 6 is similar in all respects to that of Figure 1 except that a single magnet is employed and in this instance the magnet 26 is located in the pad centrally between the ends but nearer one edge than the other. Usually the magnet is nearer the upper edge 22' than it is the lower pad edge. By this arrangement a single magnet attaches the pad to a vise jaw where it tends to depend in a balanced condition.

In the manufacture of vise jaw pads as described herein, it will be readily apparent that not only a variety of designs may be applied to the work-contacting face but that the face may also be smooth for particular uses. It has been my experience that the rougher faces are preferable for hard to grip workpieces whereas with easy to grip objects not having a polished surface, and thus not slippery, a smooth face is preferable. I do not thereby intend to be limited to a particular treatment of the gripping face of my vise attachment. However, it is important that the openings 27 into which the magnets 26 are

placed should extend from face to face in the pad. At the rear face the opening must be coextensive with the size of the magnet so that the gripping face of the latter can be disposed flush with this rear face of the pad. Likewise the forward end of the opening in the gripping face should be coextensive with the magnet so that the rubber surrounding the magnet may be compressed but with none overlying the magnet to cause a too-tight grip on an object at the risk of marring highly polished surfaces.

It will be apparent to those skilled in the art that this disclosure may be altered and changed without departing from the reasonable modifications and equivalents as come within the function and scope of the invention set forth in the claims hereafter.

What is claimed is:

1. An elastic facing for vise jaws, comprising: a pad of resilient rubber-like material shaped to cover the work-gripping face of a vise jaw and having a through opening extending from face to face thereof, and having a magnet positioned in said through opening, said magnet being of a thickness less than the thickness of said pad and being disposed in said pad so that one face of the magnet is flush with the face of the pad to be disposed against the work-gripping face of a vise jaw and the other face of the magnet underlying the plane of the work-gripping face of the pad, the compressibility of said resilient pad material being such that under compression in a normal work-gripping operation its thickness will be greater than the thickness of said magnet whereby only the pad material is pressed to the work being gripped.

2. The combination according to claim 1 in which there are at least two through openings

and magnets and they are arranged in the pad in spaced apart relation longitudinally of the pad.

3. The combination according to claim 1 in which the magnet is centrally located between the ends of the pad and disposed nearer one edge than the other.

4. The combination of a pair of opposed vise jaws and a removable facing pad positioned on each jaw, said pad being formed of resilient material and being shaped to substantially cover the work-gripping face of the jaw and having a through opening extending from face to face thereof, and having a magnet positioned in said through opening, said magnet being of a thickness less than the thickness of said pad and being disposed in said pad so that one face of the magnet is flush with the face of the pad which is disposed against the work-gripping face of the companion vise jaw and the other face of the magnet underlying the plane of the work-gripping face of the pad, the compressibility of said resilient pad material being such that under compression in a normal work-gripping operation its thickness will be greater than the thickness of said magnet whereby only the pad material is pressed to the work being gripped.
